COLLAPSIBLE WARDROBE

Abraham Stone, Brooklyn, N. Y.

Application July 6, 1933. Serial No. 679,196

7 Claims. (Cl. 312—144)

This invention has to do with containers and, while not restricted to such use, the present invention has more particular reference to a container which is designed to serve in the capacity of a wardrobe for the storage of wearing apparel in order to protect the same from deterioration or damage, by dust, moths or other hazards to which they are subjected if left in the usual clothes closets.

10 The invention aims to provide a container composed of sections made up of comparatively light weight stock, which sections, while they may be readily assembled or disassembled, are so interbraced and reinforced when assembled that the 15 interfitting portions intimately contact to effectually seal the joints against the ingress of moths or other insects and dust or other foreign matter which may prove harmful to the contents, while the seal is also effective against the egress 20 of vaporous insecticides.

The invention further comprehends a multiple compartment container having a body section which includes wall-forming portions and door-forming portions together with a partition 25 hingedly connected with a wall-forming portion so as to fold into a plane substantially parallel to the door and wall-forming portions.

As a further feature the invention embodies base and cover sections which are so constructed 30 as to effectually interfit with the upper and lower ends of the body in order to establish an effective seal in addition to serving as a means for engaging with the wall-forming portions of the body and with the partition to retain the body and partition in fixed relation when set up.

The invention further resides in the provision of means within the body structure which serves as an internal reinforcement and as a support for shelving which may be optionally employed in 40 connection with the container.

The invention aims for some of its other objects, to provide a container for wardrobe which is comparatively simple in its construction and easy to set up or knock down, and which is inexpensive to produce.

With the above recited and other objects in view which will hereinafter appear, reference is made to the following specification and accompanying drawings in which there is set forth 50 a preferred form of the invention.

In the drawings:

Fig. 1 is a perspective view of a container or wardrobe constructed in accordance with the invention and illustrating the same in its set up 55 closed condition.

Fig. 2 is an enlarged vertical transverse sectional view taken approximately on a plane indicated on the line 2—2 of Fig. 1.

Fig. 3 is a similar sectional view taken on a plane indicated on the line 3—3 of Fig. 2. 60

Fig. 4 is a horizontal sectional view taken approximately on the line 4—4 of Fig. 2.

Fig. 5 is an inner face view of either the base or top section.

Fig. 6 is a fragmentary detail sectional view 65 taken approximately on the line 6—6 of Fig. 3, and on an enlarged scale.

Fig. 7 is a similar view taken approximately on the line 7—7 of Fig. 3.

Fig. 8 is an end view of the body section in 70 partly collapsed condition.

Fig. 9 is a detail sectional view taken on line 9—9 of Fig. 1 of either the base or top portions of the container.

Referring to the drawings by characters of reference, A designates generally the body section of the container or wardrobe, B the base or end section and C the cover or other end section which sections are designed to be assembled to provide the container or wardrobe or disassembled for nesting of the same in a collapsed condition so as to occupy a minimum amount of space for storage or transportation and to afford compact arrangement for over-the-counter sales. 75

The body section A is shown in the present disclosure as consisting of a rear wall 10, side walls 11 and 12 hingedly connected to each other and doors 13 and 14 hingedly connected to the side walls 11 and 12 and which walls and doors may be formed integrally as shown or otherwise 80 within the scope of the invention. The door-forming portions 13 and 14 are of lesser height than the height of the wall-forming portions 10, 11 and 12 and are provided at their free edges with hingedly connected flaps 15 and 16. 85

The body section further includes a partition wall 17 which is hingedly attached to the inner surface of the rear wall 10 so that when the body is collapsed or folded said partition may be swung into a plane substantially parallel with 100 the rear wall and with the folded side walls and doors as illustrated in Fig. 8 of the drawings.

The base and cover or end sections B and C are substantially identical in construction and each of said sections includes a rectangular panel 105 20 attached to a cross sectional angulated frame 21 to lie within the angle, with the marginal edges 22 of the panel spaced from the inwardly directed flange 23 of the frame to define therebetween a groove or channel 24 within which is 110

- telescopically fitted the upper and lower edges of the body walls 10, 11 and 12 and the reinforcing strips 25 secured to the inner face of said walls adjacent their edges. In order to lock and retain the base and cover sections B and C in assembled relation with the body section, spring clips 26 are carried by the base and cover sections and project inwardly therefrom and are provided with bills 27 which snap behind the innermost edges of the reinforcing strips 25. When thus assembled, the sections A, B and C are interbraced to make for a rigid sealed structure. 80
- The end sections A and B, at their front sides, are formed with abutment strips 28 which are secured to the flanges 23 and project inwardly therebeyond so that the upper and lower edges of the door-forming portions 13 and 14 contact therewith and are stopped thereby when closed. The forward or free edge of the partition is provided with a channeled reinforcing strip 29 which, in addition to preventing distortion of the free edge, serves as a parting strip against which the flaps 15 and 16 impinge to seal the enclosure. This strip is recessed to provide a shoulder 30 adjacent each end thereof to accommodate the flanges 23 of the frames 21 with the edges of the flanges abutting against the said shoulders and with the extreme ends of the strip fittingly engaged in sockets 31 formed in the end sections A and B respectively. 85
- The body section A is provided with a reinforced strip 32 secured against the inner faces of each of the side walls 11 and 12 and against one face of the partition wall 17 which strips are notched at their upper ends to receive a cross bar 33 extending through an opening in the partition 17, for supporting wearing apparel suspended on the usual clothes hanger. One of the compartments may be optionally provided with one or more shelves 34 removably supported on vertical reinforcing strips 35 secured against one face of the partition 17 and against the inner face of the side wall 12 adjacent the longitudinal edges thereof. The strips 35 are recessed as at 36 to receive the shelves 34 which are provided with depending metal spring tongues 37 which slidably engage between the said strips and the partition and side wall respectively. 90
- Preferably the body section A and the panels 20 of the end sections A and B are constructed of light weight material such as plain or corrugated cardboard or light weight fiber board which is relatively inexpensive so that the container may be constructed at small cost, while the frames and the several reinforcing strips are preferably constructed of wood or other rigid material, which serves to interbrace and reinforce the walls of the container to prevent sagging or bulging thereof. 95
- What is claimed is:
1. In a knock-down wardrobe, a body section including hingedly connected side and rear wall-forming portions and a partition-forming portion hingedly connected along one edge to said rear wall-forming portion and having a reinforcing member secured over the forward edge thereof, base and cover sections each including a panel having an inwardly directed marginal flange telescopically fitted over the upper and lower edges respectively of the wall-forming portions, said flanges each having inwardly extended abutments at the front of the wardrobe providing a recess therebetween to receive the ends respectively of the reinforcing member for securing the partition-forming portion in set up relation, 100
2. In a knock-down wardrobe, a body section including a hingedly connected partition-forming portion having a reinforcing member secured to the forward edge thereof, a base section and a cover section, said base and cover sections each having a marginal flange telescopically connecting the said base and cover sections respectively with the ends of the body section and said flanges each having means providing an inner recess at the side of the section opposite to the hinge connection of said partition-forming portion to receive therein the ends respectively of the reinforcing member for securing the partition-forming portion in set up relation. 105
3. In a knock-down wardrobe, a body section including a side wall-forming portion, and a rear wall forming portion hingedly connected to said side wall-forming portion, a door-forming portion hingedly connected to said side wall-forming portion and a partition-forming portion hingedly connected along one edge to said rear wall-forming portion and having a reinforcing member secured against the forward edge thereof, base and cover sections each including a panel having an inwardly directed marginal flange telescopically connecting the said base and cover sections with the wall-forming portions, said flanges each having a pair of spaced apart inner abutments at the front of the wardrobe forming stops for the ends of the door-forming portions respectively and providing a recess therebetween to receive the ends respectively of the reinforcing member for securing the partition-forming portion in set up relation. 110
4. In a knock-down wardrobe, a body section including hingedly connected rear and side walls, a door hingedly connected to the front edge of each side wall and a vertical partition providing together with said rear and side walls laterally spaced contiguous compartments and said partition being hingedly connected to the rear wall and having its free forward edge disposed between the doors and serving as a parting strip against which the free edges of the doors impinge to seal the compartments, and said walls, doors and partition lying in substantially parallel planes when in collapsed condition and being swingable from a collapsed condition to a set up condition. 115
5. In a knock-down wardrobe, a body section including hingedly connected rear and side walls, a door hingedly connected to the front edge of each side wall and a vertical partition hingedly connected to the rear wall and having its free forward edge disposed between the doors and serving as a parting strip against which the free edges of the doors impinge to seal the laterally spaced contiguous compartments formed by said partition and said walls, and said walls, doors, and partition lying in substantially parallel planes when in collapsed condition and being swingable from a collapsed condition to a set up condition. 120
6. In a knock-down wardrobe, a body section including hingedly connected rear and side walls, a door hingedly connected to the front edge of each side walls and a vertical partition providing with said rear and side walls laterally spaced contiguous compartments and said partition being hingedly connected to the rear wall so that said walls, doors and partition lie in substantially parallel planes when in collapsed condition and are swingable from a collapsed condition to a set up condition. 125

condition, base and cover sections so constructed and arranged as to interfit with the upper and lower edges of the rear and side walls when in set up condition and means releasably holding the said base and cover sections in fixed position thereon.

5 7. In a knock-down wardrobe, a body section including hingedly connected rear and side walls and a vertical partition hingedly connected to the 10 rear wall so that said walls and partition lie in

substantially parallel planes when in collapsed condition and are swingable from a collapsed condition to a set up condition, and base and cover sections so constructed and arranged as to interfit with the upper and lower edges of the rear and side walls and with the partition to thereby hold the said walls and partition in fixed set-up condition.
